(57) **CLAIM**

The ornamental design for a segmented snack bag, as shown and described.

DESCRIPTION

FIG. 1 is a perspective view of a segmented snack bag showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a bottom plan view thereof;

FIG. 7 is a top plan view thereof;

FIG. 8 is a rear bottom perspective view thereof; and,

FIG. 9 is an exploded front view thereof, showing separated portions of the segmented snack bag.

The broken lines are claimed and directed to perforated lines that serve as an indicator of where the user may remove a section of the snack bag.
